We claim the ornamental design for a packaging for food product, as shown and described.

DESCRIPTION

FIG. 1 is a perspective view of a first embodiment of packaging for food product, showing our new design;
FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view of a second embodiment of packaging for food product;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The dash-dash and dash-dot boundary lines(s) defines the boundary of the claimed design and forms no part of the claimed design. The design is shown with symbolic break lines. The appearance of any portion of the article between the break lines forms no part of the claimed design. The broken lines depict portions of the packaging for food product that form no part of the claimed design.
